FEEDING MECHANISM FOR ROCK DRILLS

Albert Feucht, Garfield Heights, Ohio, assignor
to The Cleveland Rock Drill Company, Cleve-
land, Ohio, a corporation of Ohio

Application March 17, 1938, Serial No. 196,438

5 Claims. (Cl. 121—9)

This invention relates broadly to rock drills, but more particularly to a power actuated reversible feeding mechanism for rock drills of the drifter type.

5. Heretofore, power actuated feeding mechanisms for rock drills, generally referred to as automatic feed, even though capable of feeding the rock drill to and from the work at a greater rate of speed than that possible with a manually 10 operated feeding mechanism, were not generally adopted by the operators because such feeding mechanisms were proved unsatisfactory for drilling vertical holes or holes at an angle greater than the friction angle. With the drill support 15 positioned at such angle, the weight of the rock drill would cause it to drop to the lower end of the support, resulting in serious inconveniences and often in personal injuries. To overcome this 20 serious difficulty and prevent accidents arising therefrom, some automatic feeds were equipped with a brake mechanism which proved to be impractical because the operator could not possibly operate the brake fast enough to check the drop of the rock drill.
25. In another effort to overcome this difficulty, some of the automatic feeds were equipped with a screw carried by the support and engaged by a nut carried by the rock drill and rotated by a suitable feeding motor. In order to move the 30 drilling motor to and from the work at a rate of speed which would justify the use of automatic feed, it was necessary for the screw threads to be of a relatively steep angle, which if self locking, would soon wear to such an extent as 35 to allow the drop of the rock drill relative to the support. This construction also proved to be inefficient for checking the recoils of the drilling motor relative to its support. Due to the necessary clearance between the operative threads of 40 the screw and nut, the jars of the rock drill resulting from the reversal of its piston strokes, were transmitted to the nut, thereby accelerating the normal wear of the screw threads and often 45 resulting in a premature deterioration of the entire mechanism. Another disadvantage of this screw and nut construction, resulted from its limitation in the range of feed. Since the screw had to be at least as long as the feeding range, it was found that a long screw was not only 50 difficult and expensive to manufacture, but that after assembly, the screw being supported only at its ends, had the tendency to be easily distorted and was subjected to very severe lateral vibrations which would result in the crystallization 55 and breakage of the screw.

It is therefore one object of this invention to produce a power actuated feeding mechanism for rock drills constructed in a manner preventing the rock drill to drop relative to its support when positioned for vertical drilling or drilling at an angle greater than the friction angle. 5

Another object of this invention is to produce a feeding mechanism for rock drills including a flexible connection between the drill and its support, thereby reducing the wear of the operating 10 parts of the feeding mechanism as well as the operating cost of the drill assembly.

Another object of this invention is to provide a rock drill with a power actuated feeding mechanism operable independently of the rock drill, 15 and equipped with a device for selectively controlling its feeding speed.

Another object of this invention is to produce a feeding mechanism forming a compact and light assembly, which is strong, durable, efficient 20 and comparatively inexpensive to manufacture.

Other objects and advantages more or less ancillary to the foregoing reside in the specific construction and aggroupment of the elements 25 peculiar to this structure, as will become apparent from a complete examination of this specification.

In the drawings:

Fig. 1 is a side elevational view of a rock drill 30 embodying the invention with its support shown partly in section to illustrate details of construction.

Fig. 2 is a longitudinal sectional view taken in a plane indicated by line 2—2 in Fig. 1. 35

Fig. 3 is an end elevational view of the assembly looking in the direction of the arrows 3—3 in Fig. 1.

Fig. 4 is an enlarged longitudinal sectional view taken in a plane indicated by line 4—4 in Fig. 3. 40

Figs. 5 and 6 are views similar to Fig. 4 but taken in planes indicated by lines 5—5 and 6—6 respectively in Fig. 3.

Fig. 7 is an enlarged cross sectional view taken in a plane indicated by line 7—7 in Fig. 3. 45

Fig. 8 is a cross sectional view taken in a plane indicated by line 8—8 in Fig. 5.

Fig. 9 is a partial cross sectional view taken in a plane indicated by line 9—9 in Fig. 6.

Fig. 10 is a cross sectional view taken in a plane 50 indicated by line 10—10 in Fig. 5.

Figs. 11, 12, 13 and 14 are partial cross sectional views taken in planes indicated by lines 11—11, 12—12, 13—13 and 14—14 respectively in Fig. 6. 55

Fig. 15 is a longitudinal sectional view taken in a plane indicated by line 15—15 in Fig. 5.

Fig. 16 is a longitudinal sectional view taken in a plane indicated by line 16—16 in Fig. 5.

5 Referring to the drawings in which like symbols designate corresponding parts throughout the several views, 20 represents a fluid actuated rock drill of the drifter type having a piston (not shown) reciprocable therein for delivering impacts to a drill steel 21 slidably mounted within a front housing 22. The rock drill 20, herein-after referred to as the drilling motor, is provided with the usual guides 23 slideable within corresponding guideways 24 which extend substantially 10 the full length of a shell or support 25. This support is preferably U-shaped in cross-section with one guideway 24 formed on each inner side wall thereof, and terminated toward the left in Fig. 1, hereinafter denoted as the rear end of 15 the support, by a fixed handle 26. Within the front end of the support, there is a bracket 27 secured to one side wall of the support by bolts 28. Extending through this bracket near one side wall of the support 25, there is a bolt 29 carrying a relatively heavy compression spring 30 interposed between the head of the bolt and the bracket, while the threaded end of the bolt carries a special nut 31 having secured thereto by a cross pin 32 one end of a chain 33. The 20 other end of this chain is affixed to the other side wall of the support 25 near the rear end thereof or to the handle 26 which is shown machined to receive a bolt 34 to which the rear end of the chain is affixed by a pin 35.

35 Secured to the rear end of the drilling motor 20 by two long bolts 36, one on each side of the motor, there is the feeding mechanism including two housings 37 and 38. Secured to one side of the casing 37, there is a motive fluid connection 40 through which motive fluid may be admitted to a throttle valve 40 having a handle 41 located on the other side of the casing 37. From this throttle valve, motive fluid may be admitted into the drilling motor 20 for actuating the same 45 through a throttle valve port 42, a passage 43, an annular chamber 44 and ports 45.

The casing 37 is provided with a vertical bore 46 closed at its lower end by a plate 47 secured to the casing by bolts 48. The upper end portion of this bore is enlarged in a piston chamber 49 closed by a removable plug 50. Reciprocable within the chamber 49, there is a piston 51 having an integral stem 52 reciprocable within the bore 46, which stem has a passage 53 opening through the end thereof and capable of communication with the piston chamber 49 through a radial port 54.

50 The casing 38 is formed with a longitudinally disposed valve chamber 55 closed at one end by the casing 37 and at the other end by a removable plug 56. Reciprocable within this chamber there is a fluid actuated valve 77 formed with two annular grooves 57 and 58, opposed actuating areas 59 and 60 and two holding areas 61 and 62, the area 61 having motive fluid conveyable thereto from the groove 57 through a passage 63, while the area 62 may be supplied with motive fluid from the groove 58 through a passage 64. Within the valve chamber 55, there 65 are five annular grooves 65, 66, 67, 68 and 69. The two extreme grooves 65 and 69 open into a common exhaust passage 70, (Fig. 7) which leads to the atmosphere through an exhaust port 71 (Fig. 5), as will be explained later. The annular groove 66 is in communication with the upper

end of the piston chamber 49 through a passage 72, while the groove 68 is in communication with the lower end of this chamber through a passage 73. From the piston chamber 49, the motive fluid may be admitted to the valve actuating area 60 via a small passage 74, and to the other actuating area 59 via a similar passage 75. Each actuating area 59 and 60 is in constant communication with the atmosphere through a vent 76 of smaller cross sectional area than the passages 10 74 and 75.

15 Beside the fluid actuated valve 77, there is a feed regulating valve 78 rotatable within the casing 38 having an integral handle 79 which extends through a retaining nut 80, and held against accidental rotation by a spring pressed plunger 79' acting within corresponding notches 78' formed on the valve 78. This valve is provided with a central bore 81 leading to some operating parts of the mechanism through a passage 82 which is interconnected with the passage 70 through a groove 83 (Fig. 8). On its periphery, the valve 78 is formed with a longitudinal groove 84 capable of communication through a partly annular groove 84' (Fig. 9) with an inlet passage 20 85 (Fig. 6) which opens into the casing 37 between the throttle valve 40 and the connection 39, and through which motive fluid is supplied to the feed regulating valve 78 independently of the throttle valve 40. On its periphery, the valve 25 78 is provided with five partly circular grooves 86, 87, 88, 89 and 90. The groove 86 is connected with the central bore 81 through a port 91, while the groove 87 which is located within the same transversal plane as the groove 86, opens into the longitudinal slot 84 (Fig. 11). As shown in Fig. 12, the grooves 88 and 89 are also located within the same transversal plane with the groove 88 opening into the longitudinal groove 84, and the groove 89 connected with the central bore 81 40 through a port 92. The groove 90 extends across the longitudinal groove 84, and is capable of communication with a port 93 which opens into the annular groove 67 of the valve chamber 55.

45 Located within the casings 37 and 38 in coaxial relation with the center axis of the drilling motor 20, there is a rotatable stem 94 having its rear end rotatable within a bushing 95 held in position by a retaining plug 96, which plug also retains the usual cleansing fluid conveying tube 50 97 extending through the stem 94. The front end portion of the stem is journaled within the casing 37 and is formed with gear teeth 98 meshing with corresponding teeth 99 cut on the stem 52 of the piston 51, which teeth constitute the 55 rack and pinion assembly shown in Fig. 15. Intermediate its ends, the stem 94 is formed with an enlargement 100 having pivotally mounted therein two sets of pawls 101 and 102. In practice, each set includes three or four pawls, but for the purpose of illustration only two pawls are shown, each pawl being urged by a spring pressed plunger 103 in operative engagement with the internal teeth 104 of a ring 105 which surrounds the enlargement 100 of the stem 94, and forms 65 an integral part of a gear 106 rotatable on the stem 94. Through the ring 105, there is a port 70' leading from the gear 106 inside of the ring, through which port fluid from the exhaust passage 70 is free to flow into the ring 105 and therefrom to the atmosphere via the exhaust port 71. The ring 105 is journaled within a hardened bushing 107 having slidably therein a reciprocable wedge in the form of a sleeve 108 provided with an external annular flange 109 the side walls 75

of which form opposed actuating areas 110 and 111. The area 110 is capable of communication with either the groove 86 or 87 of the feed regulating valve 78 through a port 112 (Fig. 11), while the area 111 is capable of communication with either the groove 88 or 89 of that valve through a port 113 (Fig. 12). Internally, the sleeve 108 is formed with a substantially V-shaped annular bead 114 engageable with one end portion of the pawls 101 and 102 which protrudes from the ring 105. As shown in Fig. 5, the aforesaid end of the pawl 101 is inclined as at 115, while the corresponding end portion of the pawl 102 is provided with a V-shaped notch 116.

15 Rotatable on an axis parallel to the center axis of the stem 94, there is a worm screw 117 having a pinion 118 cut on one end thereof and journaled within a hardened bushing 119, which is cut away as at 120 for enabling operative engagement of the pinion 118 with the gear 106. The worm screw 117 is in operative engagement with a worm gear 121 rotatable on an axis perpendicular to the support 25, and having a shank 122 extending through the cover 47, on which shank is rigidly secured by a key 123 and cap screw 124 a sprocket wheel 125 meshing with the chain 33. This sprocket wheel has a sleeved extension 125' journaled within a hardened bushing 126. Beside the sprocket wheel 125, there is 20 a chain guiding roller 127 rotatable on a vertical shaft 128, which is carried by the casing 37 and held in position by a nut 129.

30 In the operation of the mechanism, motive fluid from the connection 39 is admitted to the feed regulating valve 78 via the passage 85. When the valve is positioned as shown in Figs. 3 and 9, the passage 85 is closed by the valve, causing the feeding mechanism to remain inoperative irrespective of the actuation of the drilling motor 20 which may have motive fluid supplied thereto through the throttle valve 40. If the feed regulating valve is rotated about 45° in either direction, the groove 84' will register with the passage 85, admitting motive fluid into the longitudinal groove 84 and V-shaped groove 90, from where it is admitted to the annular groove 67 of the valve chamber 55 through the port 93. From the groove 67, the motive fluid will flow into the valve groove 57 and therefrom to the holding area 61 via the port 63, thereby holding the valve in the position shown in Fig. 4, allowing the motive fluid into the upper end of the piston chamber 49 via the groove 66 and the passage 72. The motive fluid acting on the piston 51 will drive it downwardly. When the port 74 is uncovered by the piston, motive fluid from the piston chamber 49 will be admitted to the actuating area 68 for shifting the valve toward the left in Fig. 4, thereby admitting motive fluid to the lower end of the piston chamber 49 via the valve groove 58, the annular groove 68 and the passage 73, while the valve is maintained in this new position by motive fluid admitted on the holding area 62 through the port 64. The motive fluid within the lower end of the piston chamber 49 will flow to the end of the stem 52 through the port 54 and passage 53, thus cooperating with the action of the fluid on the under side of the piston 51 for driving the piston upwardly. During this upward stroke the motive fluid previously admitted into the upper end of the piston chamber 49 will exhaust through the passage 72, the grooves 66, 57 and 65, the passage 70, the port 70', and exhaust port 71. When the piston uncovers the port 75, the motive fluid will flow to the

actuating area 59 for shifting the valve into the position shown in Fig. 4. In this instance, the motive fluid previously admitted to the holding area 60 will exhaust through the vent 76. As the piston 51 is again driven downwardly, the 5 motive fluid previously admitted into the lower end of the piston chamber 49 will exhaust through the passage 73, the grooves 68, 58 and 69, the passage 70, the port 70', and exhaust port 71. As the piston 51 again uncovers the port 62 for 10 shifting the valve toward the left, the motive fluid previously admitted on the actuating area 59 will exhaust through the vent 76.

15 From the foregoing description, it is apparent that due to the alternative admission of the 15 motive fluid into the ends of the piston chamber 49, the piston 51 is made to reciprocate at a rate of speed which is controlled by a more or less complete registration of the groove 90 of the feed regulating valve 78 with the port 93, which 20 groove is of a V-shaped cross-section and of a depth gradually diminishing toward its end until it verges with the normal peripheral wall of the valve. Due to the operative engagement of the 25 rack 99 formed on the piston stem 52 with the pinion 98 formed on the longitudinally disposed stem 94, the reciprocatory motion of the piston 51 will impart an oscillatory motion to the stem 94 and to the pawls 101 and 102 carried thereby. If the feed regulating valve 78 is positioned so 30 as to cause the registration of its groove 88 (Fig. 12) with the port 113, the motive fluid from the valve-groove 84 will flow to the actuating area 111 for shifting and maintaining the wedge 108 in the position shown in Fig. 5. In this instance, 35 the valve-groove 86 (Fig. 11) will register with the port 112, affording communication of the wedge actuating area 110 with the atmosphere through the passages 91, 81, 82, and the ports 70' and 71. In this position of the wedge 108, its 40 annular bead 114 engages the pawl 101 to maintain it in the position shown in Fig. 16, that is out of engagement with the teeth 104 of the ring 105, while the pawl 102 is capable of engagement with the teeth 104 due to the position of the 45 wedge-bead 114 into the notch 116. With the pawls 101 and 102 thus positioned, the oscillatory movement imparted to the stem 94 will effect a 50 step by step rotary motion of the ring 105 in a clockwise direction in Fig. 16, which rotary motion is transmitted to its integral gear 106, and therefrom to the worm screw 117 due to the 55 operative engagement of its integral pinion 118 with the gear 106. The worm screw 117 meshing with the worm gear 121 will transmit intermittent rotary motion thereto in a counterclockwise direction in Fig. 10, causing the rotation of the sprocket wheel 125 in the same direction. This sprocket wheel meshing with the chain 33 will cause a step by step slidable movement of 60 the drilling motor 20 relative to the support 25 for feeding the motor to the work.

When it is desired to feed the drilling motor from the work, the feed regulating valve may be positioned for communication of its groove 87 65 with the port 112, and its exhaust groove 89 with the port 113. In this instance, the motive fluid previously admitted on the wedge actuating area 109 will exhaust to the atmosphere through the port 113, the groove 89 and the passages 92, 81, 70 82, and ports 70' and 71. Simultaneously, motive fluid from the longitudinal groove 84 will flow via the groove 87 and the port 112 to the actuating area 110 of the wedge 108 for shifting and maintaining the wedge at the end of its rear- 75

ward stroke, that is in a position wherein the annular bead 114 thereof engages the inclined end wall 115 of the pawl 101, allowing this pawl to engage the teeth 104 of the ring 105, while the pawl 102 is moved inwardly out of engagement with the teeth 104 by the bead 114 moved out of the notch 116 and engaging the pawl between the notch 116 and the adjacent end of the pawl. With the pawl 101 engaging the teeth 104 of the ring 105 and the pawl 102 out of engagement, the oscillatory movement imparted to the stem 94 will effect a step by step rotary movement of the ring 105 in a counterclockwise direction in Fig. 16, which rotation is transmitted to the worm gear 121 and sprocket wheel 125 in the manner above described, thereby effecting the feeding movement of the drilling motor 20 away from the work.

From the foregoing description, it will be understood that the reciprocatory movement of the power actuated piston 51 results in the feeding motion of the drilling motor 20 in either direction, which motion is transmitted thereto by the worm gear 121 and the worm 117 forming a self locking assembly preventing the worm 117 to be rotated by the gear 121. With this self locking rotation transmitting mechanism, it will be apparent that the drilling motor 20 never travels at a greater rate of speed than that resulting from the operation of its feeding mechanism, which has its speed controlled by the valve 78. For instance when drilling vertical holes, the drilling motor 20 is always locked to its support 25 due to the operative engagement of the sprocket wheel 125 with the chain 33, which sprocket wheel has its rotation checked by the self locking mechanism including the worm 117 and worm gear 121.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. The combination with a drilling motor, of feeding means for said motor comprising a housing, a fluid actuated rack reciprocable within said housing, an oscillatory member actuated by said rack, means deriving motion from the oscillatory movement of said member for transmitting a step by step feeding motion to said mo-

tor including a tooth ring, pawls carried by said member operatively engageable with one or the other side of the teeth of said ring for transmitting rotary motion thereto in one or the other direction, and fluid actuated means for selectively controlling the operative engagement of said pawls with the teeth of said ring. 5

2. In a drilling apparatus, the combination with a support having a drill slidable thereon, of a feed motor for the drill including a power actuated oscillatory element, a rotatable member driven by said element for imparting feeding motion to the drill, pawl means operatively associated with said element and member for transforming the oscillatory movement of the former into a step by step rotation of the latter in one or the other direction resulting into forward or backward feeding motion of the drill, and fluid actuated means operatively associated with said pawl means for controlling the direction of rotation of said member. 20

3. In a drilling apparatus, the combination with a support having a drill slidable thereon, of feeding means for the drill comprising a feed motor, means including a toothed member deriving motion from said motor for transmitting feeding motion to the drill, pawls selectively engageable with the teeth of said member for controlling the direction of said feeding motion, and fluid actuated means operatively associated with said pawls for controlling their engagement with the teeth of said member. 25

4. In a drilling apparatus, the combination with a support having a drill slidable thereon, of feeding means for the drill including a toothed member rotatable in two directions, means deriving motion from the rotation of said member in one or the other direction for imparting forward or backward feeding motion to the drill including pawls selectively engageable with the teeth of said member, and fluid actuated means operatively associated with said pawls for controlling their engagement with the teeth of said member. 40

5. In a drilling apparatus, the combination with a support having a drill slidable thereon, of feeding means for the drill including an oscillatory member, a driven element, clutch means between said member and element operable for transmitting rotation to said element selectively in one or the other direction, and fluid actuated means operatively associated with said clutch means for controlling the operation thereof and the consequential direction of rotation of said element. 45

ALBERT FEUCHT. 50
